PORTABLE RACK FOR SWIMMING POOL EQUIPMENT OR THE LIKE

David W. Kratz, 17 Country Life Acres, Valley of Country Life Acres, St. Louis 22, Mo.

Filed Oct. 21, 1960, Ser. No. 62,568

Term of patent 14 years

(Cl. D14—3)

FIG. 1

FIGURE 1 is a side elevational view of a portable rack for equipment or the like embodying my new design.

The dominant features of my design reside in the portions shown in full lines.

I claim:

The ornamental design for a portable rack for swimming pool equipment or the like, substantially as shown and described.
